US00D519711S

(12) **United States Design Patent** (10) **Patent No.:** **US D519,711 S**
Dreano (45) **Date of Patent:** **** May 2, 2006**

(54) **HAM**

(75) Inventor: **Claude Dreano**, Mauron (FR)

(73) Assignee: **Armor Inox SA**, Mauron (FR)

(**) Term: **14 Years**

(21) Appl. No.: **29/175,649**

(22) Filed: **Feb. 10, 2003**

(30) **Foreign Application Priority Data**

Aug. 8, 2002 (FR) 02 4852

(51) **LOC (8) Cl.** **01-01**

(52) **U.S. Cl.** **D1/121; D1/199**

(58) **Field of Classification Search** D1/106,
D1/199, 121, 125, 128-129, 100, 101, 107;
426/412, 144, 402, 76, 284, 92, 518, 104,
426/574, 513, 802; D7/672

See application file for complete search history.
